CLAIM

The ornamental design for an earphone box, as shown and described.

DESCRIPTION

FIG. 1 is a front view of an earphone box showing the new design;

FIG. 2 is a left view thereof;

FIG. 3 is a right view thereof;

FIG. 4 is a top view thereof;

FIG. 5 is a bottom view thereof; and,

FIG. 6 is a front-left-top perspective thereof.

The broken lines shown in the drawings depict portions of the earphone box that form no part of the claimed design.
